WINDOW SHADE PULL OR SIMILAR ARTICLE

Bernard Weisman, Brooklyn, N.Y.

Application February 9, 1959, Serial No. 54,514

Term of patent 14 years

(Cl. D21—1)

FIG. 1

FIG. 2

FIG. 3

FIG. 4

FIG. 5

Fig. 1 is a front elevational view of a window shade pull or similar article showing my new design;

Fig. 2 is a side elevational view thereof;

Fig. 3 is a rear elevational view thereof;

Fig. 4 is a sectional view, on an enlarged scale, taken on the line 4—4 of Fig. 1; and

Fig. 5 is a sectional view, on an enlarged scale, taken on the line 5—5 of Fig. 1.

The fragmentary broken line showing of a window shade is for illustrative purposes only.

I claim:

The ornamental design for a window shade pull or similar article, substantially as shown and described.
